Application March 15, 1940, Serial No. 324,210

19 Claims. (Cl. 29—48)

This invention relates to improvements in systems including structures which are to be intermittently moved between accurately determined positions.

One of the features of the present invention is the provision of mechanical elements including a reversible source of power which upon operation in one direction produce a harmonic motion of the structure through greater than a finally-desired distance, in association with means for effecting a reversal of the source of power and thereby producing a retrograde movement of the structure to the desired position.

Another feature of the invention is the provision of mechanical elements including a reversible source of power, together with a clutch and worm wheel drive for moving the structure, and control means by which the source of power operates in one direction with a positive engagement of the clutch for moving these elements and producing a movement of greater than a finally-required amount, followed by a reversal of the source of power and a retrograde operation through the worm wheel and worm so that the engagement of a structure with a stop produces a reaction between the worm wheel and worm which effects a relative opening of the clutch.

A further feature of the invention is the provision of elements including a reversible source of power, a clutch, a worm assembly including a spring for normally closing the clutch, a worm wheel engaged with the worm, and means for moving the structure from the worm wheel, wherewith a movement of the source of power in one direction causes the structure to turn through a distance greater than that finally desired, together with control means for reversing the source of power so that the structure is given a retrograde movement until engaged with a stop and thereafter reaction between the worm and worm wheel causes the clutch to open against the action of the spring and the spring is effective for holding the structure engaged with said stop.

A further feature of the invention is the provision of mechanical elements and electrical structures by which a reversible electric motor is caused to effect a forward movement of the structure through more than the finally-desired distance, and thereupon mechanical control of the electrical system causes a reversal of the motor and a retrograde movement of the structure until it engages a stop, together with direction-controlled switch means for determining the operation of the electrical system.

A further feature of the invention is the pro-

vision of reversible mechanical means for operating a structure, and including a revoluble body carrying a crank shaft which is rotated during the revolution of the body and effectively presents its crank pin for operation of an intermediate member whereby to produce a harmonically accelerated and decelerated movement of this intermediate member and thereby produce a corresponding harmonic motion of the structure to be moved.

Another feature of the present invention is the provision of means for accurately positioning and guiding a revoluble structure and permitting the take-up of looseness in parts and a centralizing of the path of movement thereof.

A further feature of the present invention is the provision of means for accomplishing the movement of an intermittently-driven member from one position to another accurately, and through the employment of elements effective for reducing the necessary power during a major part of each movement and for assuring definite positioning of the member in its final position.

With these and other features as objects in view, an illustrative form of practicing the invention is set out on the accompanying drawings in which:

Figure 1 is a side elevation of a machine embodying the present invention, with parts eliminated for better showing the general construction of the apparatus.

Figure 2 is a diagrammatic view, corresponding to a top view of Fig. 1, and indicating the successive individual turrets and stations.

Figure 3 is an upright fragmentary sectional view, on a larger scale than that of Figs. 1 and 2, substantially through the axis of the turret.

Figure 4 is a horizontal sectional view substantially on line 4—4 of Fig. 3.

Figure 14 is a circuit diagram.

An illustrative application of the present invention to a machine tool comprising a turret rotatable about a central vertical column of a machine base, and employing a plurality of individual machine units, is shown in these drawings. The general machine base B is provided with a turret table T which receives a predetermined number of vises or like fixtures F which are secured to the table and are carried in rotation therewith about the central column provided by the machine. This central column includes an upstanding member M which, in the illustrative form, has a radial flange Ma at its lower end for engaging the base B and having a top surface for supporting the turret table T. Above the member M is a structure N for supporting certain of the machine units, and including a hollow cap member C within which is rotatably mounted a central spindle S.

In the illustrative form of Figs. 1 and 2, the turret table T is provided with twelve equidistant vises or fixtures F; and the machine base is illustrated as provided with eleven machining units P1, P2, P3 . . . P11. The specific construction and arrangement of these individual units, and their particular mounting with respect to the base and turret, depends upon the article which is to be fabricated while supported in a fixture F. Illustrative mounting and employment of such units are shown in Figs. 1 and 2, and correspond generally to the arrangements set out in the Kingsbury and Swahnberg Patent 2,011,487 and the Swahnberg Patent 2,011,488. In the illustrative showing herein, certain of these units are positioned on the member N with their tool axes vertically above the corresponding stations, while two of the units are located on angle brackets supported on the base member B. It will be understood that these tool units are interchangeable, and can be positioned and adjusted as required for the article to be made, and are fitted with the requisite drills, reamers, taps, etc., for performing the operation. These units are thus provided with the tools, and are individually adjusted for operation at their maximum efficiency. Thus, one unit may perform a rough drilling operation, a second unit will perform a finish-boring operation, and a third unit a tapping operation upon the article as it successively moves from station to station in the intermittent movement of the turret table.

Each of the machining units or tool heads P1, P2, P3 . . . is illustratively provided with a head driving motor HM-1, HM-2, HM-3 . . . , for causing the individual unit to perform its cycle. At the start and close of each cycle, the individual switch HS-1, HS-2, HS-3 . . . of the unit is in closed position. Each unit further has a detaining means which stops it at the close of its cycle, and may be released upon energization of the individual trip coil HT-1, HT-2, HT-3 . . .

The driving system of the present invention is here illustrated as employed for accomplishing the intermittent movement of the table T. The structure includes a platform 20 which is provided with a nut 21 engaged with a thread

22 on the lower end of the spindle S. This platform may thus be raised and lowered by rotating the spindle S by employment of a wrench or other suitable tool on the squared upper end thereof. When the platform 20 has been lowered to its bottom position, it rests upon rolls 23 carried by the plate Ba. The inner end of the platform 20 has the fingers 24 which engage a guide post 25 and prevent rotation of the platform about the axis of the spindle S. It will be noted that the spindle S passes through and is guided by the upstanding reinforcing web structure 26 of the platform 20. When the platform 20 is lowered (dotted lines Figure 3) onto the rollers 23, the spindle S may be drawn out of the top of the machine, and then the platform, with the turret-driving structure, may be rolled through a front door of the base B. When the platform 20 and the driving structure have been raised into the operating position, the spindle may be clamped against accidental rotation by a strap 27 having a pin 28 which engages in an aperture in the base of the platform 20. The spindle S is supported by an anti-friction bearing 29 carried in part by the member M; the downward thrust of the spindle S is transmitted through the dowel pin 30 to the sleeve 31 and thus to the inner member of the anti-friction bearing 29. The lower end Sa of the spindle S is guided in a suitable aperture of the base plate Ba.

The outer wall of the member M has a flange 35 which supports a hardened ring 36 with a truly concentric external surface. This ring 36 is held by the locating pin 37 and by the cap screws 38.

The turret table T rests upon the general machine structure, and is provided with a plurality of guiding rollers 40 which engage with the peripheral face of the hardened ring 36. Each of these rollers is carried by a bushing 41 mounted on an eccentric portion 42 of a pivot pin 43 which has an enlarged downwardly-divergent conical upper end. This upper end also has a hexagonal recess 43a for engagement by a proper wrench for turning the pivot pin and thereby adjusting the corresponding roller 40. A plate 44 has a conical aperture to fit the upper end of the pivot pin and is held in position and against rotation by means of screws 45a; and screws 45 may be tightened, after an adjustment of the roll 40 to hold the pivot pin against displacement, by clamping the plate 44 and ring 44a together, so that ring 44a presses against the enlarged end of pivot pin 43.

An internally-cut gear ring 50 is secured to the underface of the turret table T by bolts 51, and is utilized in producing the desired movement of the turret table.

The drive for the turret table is accomplished from motor mechanism supported on the platform 20, and in the illustrative form, two units TM are provided in order to equalize the pressure effects, although it is obvious that one or more units may be employed in accordance with the requirements of the particular machine. As these units are essentially identical in construction, a description of one of them will serve for both. The position of each such unit upon the platform 20 is adjusted and determined in accordance with the relative diameters of the gear ring 50 and the driving pinion 105 to assure proper meshing, the size of the pinion 105 being selected as a fraction of the size of ring 50 corresponding to the number of stations

at which the turret table is to come to a standstill.

The turret driving unit TM is provided with an electric motor IM for indexing, having a casing 60 and a shaft 61 in splined engagement with a clutch member 62 carried by anti-friction bearings 63 mounted in a casting 64 secured to the main casting 65 of the turret driving apparatus. The inner clutch member 66 provides a space within which are mounted the clutch plates 67 so that these plates engage when the members 66 and 62 are brought toward one another. The clutch member 66 is illustrated as formed integral with a worm 68 and with the reduced end portion 69 which is supported by anti-friction bearings in a sleeve member 71 which is normally urged toward the right in Fig. 10 by a pressure spring 72 which reacts against a plate 73 which may be adjusted in position by a seating screw 74 supported by an end member 75 attached to the main casting 65.

The worm 68 engages with worm wheel teeth 80 formed on a ring 81 which is secured by a dowel pin 82 to a main rotating body 83. This main rotating body has the plain bearing bushings 84 for supporting the pins 85 (illustrated as two in number) which have the crank arms 86 provided with crank pins 87. At the other end of each pin 85 it is splined for engagement with a gear 88 which is in constant rolling engagement with a gear member 89 which is secured to the end plate 65a of the turret driving mechanism by means of the locating pin 90 and the cap screws 91. The main body 83 is supported by anti-friction bearings 92 upon a central shaft member 93 which is carried by anti-friction bearings 94 with respect to the end plate 65a. The central shaft 93 has a spline 95 at the upper end in Fig. 11, for engagement with a driving plate 96 which in turn is carried by anti-friction bearings 97 in the end plate 98 of the main housing 65. The driving plate 96 is driven from a disk 99 in one side of which are formed radial grooves 100 having parallel walls. These grooves are shown (Fig. 13) as spaced 180 degrees apart and receive the sliding blocks 101 in which the crank pins 87 are rotatable. In the other side of the disk 99 are formed grooves 102 for receiving the driving blocks 103 pivoted on studs 104 secured in the end plate 98; this assures an equalization of pressure efforts between the two crank pins 87.

The spline 95 of the central shaft 93 also receives the drive pinion 105 which is in mesh with the internally-cut gear ring 50 on the turret table T.

The units TM are fixedly secured to the platform 20 at such positions that, when the platform 20 is at rest, the pinions 105 are in proper pitch-circle relationship to the gear ring 50, and are thus capable of being engaged therewith, with slight relative movements of the parts if the teeth and grooves do not properly mesh.

It is preferred to form the end plate 98 with a flange 98a (Figures 3 and 11) which is closely received in a corresponding aperture of the radial flange Ma, the end face of the plate 98 coming into abutting relationship with the under surface of the flange Ma and thereby limiting the upward movement of the individual unit TM and of the platform 20 which supports the same. However, by construction, the pinion 105 assumes a predetermined final position, after actuation of the motor 60, which is identical with its initial position, in the form shown; and

the parts are so designed and located by dowel pins with respect to one another, that normally the turret driving mechanism can be raised with the platform 20 and immediately find proper engagement. It has been found desirable to employ a timing pin 106, as shown in dotted lines in Figure 11, to hold the body 83 and therewith the central shaft 93 and the pinion 105 against accidental movements, when the parts are disassembled.

As shown in Figs. 7, 8 and 9, the undersurface of the turret table T is formed with a plurality of substantially radial recesses 110, equal in number to the number of stations at which the turret 15 is to be held at a standstill. Each of these recesses receives a pair of hardened blocks 111, 112 which are held in position by cap screws 113. The block 111 is at the normally-advancing edge 20 of the turret (as indicated by the arrow in Fig. 9) and has a bevelled surface 115. The block 112 has an upright end surface 116 at its normally-trailing edge. It will be noted that the downwardly directed surface 117 on the turret table rests upon the corresponding surface 118 of the 25 fixed structure, being in the illustrative showing provided at the top of the outer edge of the peripheral flange Ma; and thus serves to support the turret table closely adjacent the positions of the several fixtures or vises F.

30 As shown in Fig. 7, these pairs of blocks 111, 112 cooperate with a turret-position controlling or lock pin 120 which at its upper end (Fig. 9) is cut away to provide one substantially upright face 121 positioned radially with respect to the central axis of the apparatus, and is also provided with a bevelled surface 122 opposite to the surface 121. The surface 121 can engage with the upright face 116 of the block 112, in the course of a retrograde movement of the turret and thereby 35 determine a position of standstill for the turret; while the bevelled or inclined surface 122 cooperates with the bevelled surface 115 of the block 111 to permit the turret to move in the normally-advancing direction away from such a 40 position of standstill.

45 As shown in Fig. 7, the lock pin 120 is supported in a sleeve 123 mounted in an aperture of a bracket 124 secured inside of the base member B. The sleeve 123 has a radial lower flange 125. The pin 120 is hollow and receives a spring 126 which normally tends to thrust it upward and into a recess 110. This spring reacts against a thrust block or a spring shoe 127 which is held in position by a pin 128 which is received in apertures of the sleeve 123 and extends through slots 129 of the wall of the pin 120. The lower end of the pin 120 is threaded internally and receives an actuating cap 130 having a projecting radial flange which engages with the shock washer 131 at the limit of upward movement of the pin 120, and presses this washer 131 against the flange 125 and thereby cushions the pin 120 and brings it to a standstill as it enters the notch 110 with the surface 121 dropping rapidly past the surface 116. A switch housing 132 is secured to the flange 125 by the screws 133 and receives a lock pin switch LPS which is provided with the actuating plunger 135 for actuation by the actuating cap 130 upon the downward movement of the same as produced by the inner engagement of the bevelled surfaces 122 and 115 at an early stage of the forward movement of the turret from one station toward the next.

70 Means are included in the illustrated structure for assuring a proper timing and sequence of

operations. In this illustrative form, as set out in the aforesaid patents, each of the machining units P₁, P₂, P₃, etc., is provided with a switch HS-1, HS-2, HS-3 . . . which is open during the normal course of operation of the unit, but is closed upon the return of the parts of the unit to a withdrawn position at which there is no interference between the unit tool (such as a drill, reamer, etc.) and the indexing movement of the turret with the fixtures and articles thereon.

A manner of connecting the electrical elements, with conventionalized showing of relays employed, is set forth in Fig. 14. In this figure, the apparatus is assumed to be supplied with three-phase alternating current when the main switch SW is closed. Current then flows through the phase conductors 140, 141 and 142 and the branch conductors 143 to the forward relay FR and the reverse relay RR and thence in accordance with the selective energization of these relays to the indexing motor IM, and also flows through the branch conductors 144 for energizing the motors HM-1, HM-2, HM-3 . . . of the individual work units.

In this circuit diagram, it will be assumed that a lower position of a switch is the normal one, and that the switch contacts of a relay are raised upon energization of the relay, and that the single circuit switches AIS, MIS, HS-1, HS-2 . . . are normally in the lower and open position.

The control circuits are supplied by a conductor 150 which is branched from phase conductor 140 and may include a fuse 151. This conductor 150 connects the several switches HS-1, HS-2, HS-3 . . . of the several working units in series, these switches being so constructed and arranged in the particular unit that they are individually closed when the individual unit has performed its cycle and returned to a rest position in which the turret may be indexed. Such arrangements of parts are described in the Kingsbury et al. Patent 2,011,487 and the Swahnberg Patent 2,011,488. From the last of these head switches, this series circuit continues by a conductor 152 to the automatic indexing switch AIS and the hand indexing switch MIS which are connected in parallel, and also to a lower contactor of the jog switch JS. This jog switch JS is shown as a two-pole switch that, when closed, permits completion of holding circuits for assuring completion of cycles of automatic operation and, when open, permits "jogging," e. g. movements of distance and duration controlled manually by closing and opening of the manual indexing switch MIS. When either the automatic or the manual indexing switch is closed, current flows to the conductor 153 and to the normally-closed contacts of a control relay CR-2 and thence by conductor 154 to the coil of a control relay CR-1 with a return by conductor 155 to phase conductor 142. Control relay CR-1 is thus energized and closes.

When the relay CR-1 closes, current can flow from conductor 152, through the lower contacts and blade of the jog switch JS to conductor 156, through now-closed contacts of relay CR-1 to conductor 153; this holding circuit through the switch JS shunts the indexing switches AIS and MIS, so that these switches may now be opened without disturbing the energization of the coil of relay CR-1.

Further, the closing of relay CR-1 establishes a circuit from conductor 150 through the overload circuit-breaker 157, conductor 158, now-

closed contacts of relay CR-1, conductor 159, to the coil of the forward relay FR. The forward relay FR closes and the indexing motor IM begins to move in a forward direction.

5 After a short time interval, the beveled surface 115 engages the lock pin 120 and depresses the same and thereby moves the lock pin switch LPS into its lower position. A circuit is now established from conductor 150 through the overload

10 circuit breaker 157 and by conductor 158 to an upper contact of the jog switch JS. This jog switch JS closes a continuance of this new circuit by conductor 160 to lock pin switch LPS and through the lower closed contact thereof to conductor 161, through a normally closed contact in relay CR-2, conductor 162, the coil of relay CR-2 to conductor 155 and thus back to phase conductor 142. Control relay CR-2 is energized and closes.

20 The closing of control relay CR-2 establishes contacts which connect conductor 156 to conductor 162 to establish a holding circuit for relay CR-2 under control of the lower contacts of jog switch JS. The coil of the closed relay CR-1

25 has been supplied through normally closed contacts of relay CR-2 which have connected conductors 153 and 154; but now the closing of relay CR-2 opens the circuit by conductors 153, 154 and relay CR-1 is de-energized. At the

30 same time, however, a circuit is established from conductor 161 by now-closed contacts of relay CR-2 direct to conductor 159, so that the forward relay FR remains energized and the indexing motor IM continues to turn forwardly

35 under control of the jog switch JS and the lock pin switch LPS.

When the turret has reached the new station in the course of the indexing movement, the lock pin 120 snaps into the corresponding recess

40 110 and the lock pin switch LPS opens the contact to conductor 161 and again closes a contact to conductor 163. By opening the circuit through conductor 161, the current flowing

45 through the coil of forward relay FR ceases and the indexing motor IM is deenergized. The closure of contact at lock pin switch LPS to conductor 163 establishes a circuit from conductor 150 through conductor 158, the upper contacts of

50 jog switch JS, conductor 160, switch LPS, conductor 163, normally-closed contacts of relay CR-1 for conductor 164, the coil of reverse relay RR, to conductor 155 and back to phase conductor 142. The reverse relay RR is energized and closes, and current now flows to the

55 indexing motor IM with phase reversal so that this motor is plugged and then reversed in direction of movement.

The closing of relay RR also closes control contacts by which conductor 158 is connected to conductor 165 and thence through a now-closed contact of relay CR-2, by conductor 166 to the coil of the head tripping relay HTR, with a return by conductor 167 to conductor 155 and thus to the phase conductor 142. The energization of relay HTR closes circuits from the

60 phase conductors 140, 141, 142 to the head tripping conductors 170, and the tripping coils HT-1, HT-2, HT-3 . . . of the individual heads are energized. It will be noted that these

65 tripping coils are connected in delta for each three working units and thus the loading of the three-phase line is substantially balanced, which is an extremely desirable condition when a great number of heads are employed. The effect of energizing the coils HT-1, HT-2, HT-3 . . . is

to release the detaining means which previously have been holding the working units against starting a cycle. Therefore, the individual units are now operated for initiating their individual cycles.

Meanwhile, the retrograde movement of the indexing motor IM has caused the upright face 116 of the corresponding recess 110 of the turret table to be brought against the upright face 121 of the lock pin 120, so that the turret is brought accurately to the station and is maintained thereat.

As the work units begin to operate, their individual switches HS-1, HS-2, HS-3 . . . are opened. The opening of any one of these switches breaks the circuit through conductors 150, 152 to the lower contacts of the jog switch JS and through conductors 153, 154 and relay CR-2 drops to the normally open position.

The individual work units now perform their functions in individual cyclic fashion and withdraw until all of the head switches HS-1, HS-2, HS-3 . . . are closed. The series circuit through conductors 150, 152 is now reestablished, and a further manual indexing can be accomplished by closing the hand indexing switch MIS.

To describe a cycle of operation of the structure, it will be assumed that all of the working heads or units P1, P2, P3 . . . have individually completed their cycles and have returned to the withdrawn position in which their corresponding individual switches HS-1, HS-2, HS-3 . . . are closed, and in which the individual units are ready for a further performance of their cycles upon energization of the individual trip coils HT-1, HT-2, HT-3 . . . The automatic indexing switch AIS is assumed to be open, so that the apparatus will perform on a semi-automatic basis; that is, upon a single manual manipulation, an indexing is accomplished and each of the working units or heads P1, P2, P3 . . . performs a single cycle of operation, and then all parts return to a position at which a further indexing and working can be effected by a second manual operation, etc. The manual indexing switch MIS is normally open. The jog switch JS is in closed position. The lock pin switch LPS is in raised position, as the lock pin 120 is in its uppermost position in a recess 110.

Upon manual operation of the switch MIS, a circuit is established by which relay CR-1 is energized, and this in turn closes the forward relay FR, and the indexing motor IM is energized for forward movement. The rotation of motor IM causes revolution of its shaft 61 and of the worm 63 in the direction shown by the arrows, and the worm 63 drives the worm wheel 80 so that the reaction thrust is toward the right in Fig. 10 and the clutch 67 is held closed so that essentially a positive drive is effected, and the main rotating body 83 turns in the direction of the arrow (Fig. 11) carrying the crank shafts 85 with it. The gears 83 roll on the stationary gear 89 and the crank shafts 85 are thus rotated so that their cranks 87 press the blocks 101 against the walls of the grooves 100 of the disk 99 and the latter is driven by a harmonic motion so that there is an acceleration to a maximum speed (when the blocks 101 are substantially at the outer ends of the grooves 100 in the illustrated form), and therewith the driving head 96 is driven and carries the central shaft 93, 95 in rotation with it and the pinion 105 drives the gear ring 50 secured to the turret table. In this way, a harmonic motion of the turret table is pro-

duced with acceleration and deceleration. The parts are so constructed and arranged that the turret table is thus driven through a slightly greater angle than that corresponding to the angular spacing of the stations at which the turret is to be brought to a standstill.

Shortly after the turret begins to move, the lock pin 120 is depressed and the switch LPS is moved downward. A circuit is established through 10 conductor 160, switch LPS, conductor 161, normally closed contacts of relay CR-2, conductor 162, and the coil of the holding relay CR-2 is closed. Relay CR-2 now sets up its own holding circuit from conductor 159 to conductor 162, and 15 likewise establishes a circuit from conductors 161 to 159 to maintain energization of the forward relay FR.

As the turret passes the position at which it is to be held at a standstill, the lock pin 120 is 20 pressed upward by its spring 126 and engages in the recess 110 corresponding to this new station. This upward movement of the lock pin 120 produces a shifting of the lock pin switch LPS, so that the circuits are now re-established to terminate energization of the forward relay FR through conductor 161 and to energize the reverse relay RR and the motor is plugged to a standstill and then caused to turn in a retrograde direction. At this time, the worm 63 is rotated opposite to 30 the direction of the arrow, and the reaction of the worm in the worm wheel 80 causes the worm to move relatively toward the left (Fig. 10) when resistance is encountered, against the action of spring 72. Such resistance occurs when the upright face 121 of the lock pin 120 engages the upright face 116 of the block 112, during the retrograde movement of the turret. This leftward shifting of the worm 63 and its shaft operates to 35 disengage the clutch 67 so that the indexing motor IM may continue to turn without driving the system.

During the course of the retrograde movement of the turret, contacts of the relay RR serve to 40 energize the conductors 165, 166 so that the trip coils HT-1, HT-2, HT-3 . . . are energized and effect an initiation of the operation of the individual working units or heads P1, P2, P3 . . . It will be understood that these units are so constructed and arranged that a forward traverse 45 occurs before the tools come into the paths of any parts of the turret, fixtures or article of work, so that the short retrograde movement of the turret table causes no difficulty.

During the course of the operation of the working units or heads P1, P2, P3 . . ., the spring 72 presses the worm 63 against the worm wheel 80, and acts through the system to prevent any looseness or back-lash, and holds the turret under 50 resilient pressure in a retrograde direction so that the block 112 remains pressed tightly against the lock pin 120.

As each work unit completes its cycle and returns to and is detained in its withdrawn position, the corresponding switch HS-1, HS-2, HS-3 . . . is closed. Ultimately, the system is restored to its forward condition, and a further cycle can now be initiated by again closing the manual indexing switch MIS.

If it is desired to have a completely automatic operation, in which indexing movements automatically alternate with the performance of individual cycles of completed movements by the working units or heads P1, P2, P3 . . ., the automatic indexing switch AIS is closed and remains closed. As this switch AIS is in multiple

with the manual switch MIS, the completion of a working cycle by the last of the working units or heads P1, P2, P3 . . . will result in the closure in the last of the switches HS-1, HS-2, HS-3 . . . and current will now flow through conductors 150, 152 and switch AIS and provoke directly a further indexing movement.

During the initial adjustment of the structures, and at other times, it is desirable to be able to cause the turret to move forward by a "jogging" or "inching" movement under strict control of the operator. This can be effected by opening the jog switch JS. Upon then closing the manual indexing switch MIS, current can flow from conductor 152 to conductor 153, through normally closed contacts of relay CR-2, conductor 154 and energize the coil of relay CR-1; this relay CR-1 closes, and forward relay FR is closed and the index motor IM can turn forwardly so long as the switch MIS is held closed. Upon releasing this switch, the relay CR-1 opens and therewith the forward relay FR and the system comes to a standstill again; it will be noted that the opening of the jog switch JS does not permit closing of the holding circuit through the relay CR-1, as the path between conductors 152 and 156 is interrupted. Further, the jog switch JS opens the path between conductors 158 and 160, so that the lock pin switch LPS remains de-energized, and no current can flow through the coils of the relay CR-2 or the reverse relay RR; hence, the turret does not perform its succession of forward and retrograde movement under control of the lock pin switch LPS; nor are the work units released, as the circuit through conductors 165, 166 is interrupted both at the relay CR-2 and at the reverse relay RR.

As shown in Figures 3, 6, 7 and 10, it is preferred to form the driving pinion 105 and the ring 50 with skew gear teeth. The angle and direction of the teeth are so devised that the reaction between the teeth is effective during the forward movement of the turret driving unit TM for producing an upward component of motion of this table, so that the pressure between the bearing surfaces 117, 118 is relieved in part and a rapid and free indexing movement of the table or dial T can be accomplished. This arrangement of skew teeth is further effective upon reversal of the indexing unit TM to produce a downward component of the movement upon the table T, which produces forces at the surfaces 117, 118 tending to act as a brake during the short retrograde movement; and also serving to pull the table down for accurate registration at the time it is brought to a standstill in its retrograde movement by the action of the lock pin 120. It will be noted that the lifting forces developed during the forward movement are transmitted to the platform 20 and thus essentially balance themselves as the units must obviously have like arrangement of parts; while the downward forces during retrograde movement are accomplished by the abutting engagement of parts of the unit with the flange Ma closely adjacent to the point at which the downward pressure itself is being exerted, so that there is little strain upon the table T or the flange Ma tending to warp either of them from their true positions.

It will be noted from Figs. 3, 5 and 6 that the turret table T is not journaled and guided concentrically in a direct manner by the central

element M, but rests upon ways provided by the upper surface of the flange Ma. The hardened steel ring 36 is secured to the central structure M in concentricity with the general axis. The axis of the turret table is determined by the positions given the several rollers 40, and these rollers can be adjusted and secured to obtain and maintain a desired relative radial position for the several fixtures. If looseness develops, or it is otherwise desired to adjust the parts, this is effected by releasing the central or hold-down lock screws 45 (Fig. 5), so that the plate 44 and ring 44a are loosened. A suitable wrench is then inserted in the hexagonal recess 43a of the roller pivot pin 43 and the latter is turned so that its eccentric portion 42 causes the roller 40 to move toward or away from the common axis. When proper adjustments have been effected, the binding engagement between the plate 44 and the upper conical end of pin 43 is again effected, by tightening the screws 45 which tend to relatively raise the clamping ring 44a. It will be noted that the entire assembly can be withdrawn by releasing the hold-down screws 45a.

It is obvious that the invention is not limited to the illustrative form shown and described, but may be practiced in many ways within the scope of the appended claims.

We claim:

1. In a driving system for a turret or like structure which is to be moved successively through predetermined intervals, a reversible source of power, means driven from the source of power to actuate the structure, a stop member for limiting retrograde movement of the structure upon reversal of the source of power, a slip clutch included in said driving means for disconnecting the source of power from driving relationship with the structure when the latter is engaged with the stop member, means effective for re-engaging said clutch and for holding the structure against said stop member, means for initiating forward movement of the source of power, and means for effecting reversal of movement of said source of power after a predetermined relative forward movement of said structure.

2. A system as in claim 1, in which the initiating means includes an initiating switch, and the initiating and reversing means include control relays and circuits controlled thereby for causing the source of power to be energized for automatically completing a cycle of movement, and also including a jog switch and circuits connected therewith for establishing selective holding circuits for said relays in one position of the jog switch for assuring the completion of the cycle, said jog switch and its said associated circuits being effective in another position of the jog switch for preventing establishment of the holding circuits and assuring a continued forward movement of the source of movement under control of the initiating switch.

3. In a driving system for a turret or like structure which is to be moved successively through predetermined intervals, comprising a reversible source of power, a worm driven by said source of power, a worm wheel in mesh with the worm, means actuated by the worm wheel for moving said structure, a spring effective for moving the worm axially for thereby producing a retrograde movement of the wheel, a slip clutch included between said source of power and said worm and normally held engaged by said spring, a stop for limiting the retrograde movement of

the structure, means for initiating forward movement of the source of power, and means for effecting reversal of the source of power upon a predetermined forward movement of the structure.

4. A system as in claim 3, in which the reversing means includes a switch, and said stop is constructed and arranged to move upon a predetermined forward movement of the structure, said stop including means for actuating said switch.

5. A turret mechanism including a turret, a gear on the turret, a driving pinion in mesh with the gear, a revolute member connected for rotating the pinion, said revolute member having at least one substantially radial groove therein, a source of power, a revolute body carrying a crank shaft eccentric to its own axis, a crank pin on said shaft engaged in said groove, a first gear on said crank shaft, and a fixed gear in mesh with said first gear, said revolute body and fixed gear being effective to cause a rotation of the crank shaft about its own axis during the revolution of said body and to cause said crank pin to move in said radial groove and thereby produce a harmonic accelerating and decelerating movement of said rotatable member and of said turret.

6. A turret mechanism including a turret, a gear on the turret, a driving pinion in mesh with the gear, a revolute member connected for rotating the pinion, said revolute member having at least one substantially radial groove therein, a source of power, a revolute body carrying a crank shaft eccentric to its own axis, a crank pin on said shaft engaged in said groove, said body being concentric with said member, a first gear on said crank shaft, and a fixed gear in mesh with said first gear, said revolute body and fixed gear being effective to cause a rotation of the crank shaft about its own axis during the revolution of said body and to cause said crank pin to move in said radial groove and thereby produce a harmonic accelerating and decelerating movement of said rotatable member and of said turret.

7. In a turret mechanism, a reversible electric motor and means driven thereby for moving the turret in either direction, forward and reverse switching means for the motor, an initiating relay, a holding relay, circuit means including contacts of the initiating relay for energizing said switching means to produce forward movement of the motor and turret, means responsive to the turret movement and to the position of the initiating relay for energizing the holding relay, circuit means including contacts of said holding relay for de-energizing the initiating relay and for maintaining energization of the switching means when the holding relay is closed, a jog switch, and circuit means including said jog switch and said responsive means for further energizing the switching means in one position of the jog switch and thereby producing a reversal of the motor and retrograde movement of the turret following a predetermined forward movement.

8. A turret mechanism comprising a reversible electric motor, a clutch driven from the motor, a worm driven from the clutch, and a spring effective upon the worm to move the same axially and thereby hold the clutch engaged, a worm wheel in mesh with the worm, means driven by the worm wheel for turning the turret, means for reversing the motor, a stop for limiting retrograde movement of the turret, the worm, worm wheel, clutch and spring being so constructed and

arranged that the clutch engages during rotation of the motor for producing forward movement, and the worm threads in the worm wheel when the turret is detained by the stop and thereby moves axially against the spring for opening the clutch, said spring being then effective for pressing the worm axially during its engagement with the worm wheel and thereby holding the turret against said stop.

10. A turret mechanism including a turret to be intermittently moved through a predetermined distance, a reversible source of power, an axially movable member driven by said source and having a worm thereon, a spring for moving the member axially, a stop to limit retrograde movement of the turret, a worm wheel in mesh with the worm, means driven by the worm wheel for moving the turret, and means for energizing the source of power including elements for producing a forward movement thereof whereby the turret is moved past the finally-desired position, and elements effective after said forward movement for causing the source of power to be reversely energized for retrograde movement of the turret until the latter engages the stop whereby the worm wheel is brought to a standstill, the worm thereupon threading in the worm wheel and moving axially against the action of the spring, said spring being thereby effective through the worm and worm wheel for holding the turret engaged with the stop.

10. A turret mechanism comprising a base member and a revolute turret member, one of said members having a circular guide ring, the other said member having a plurality of guiding members; each said guiding member including a roller engaged with the guide ring, and pivot means for said roller, said pivot means including an eccentric portion so that a rotation of the pivot means will cause movement of the roller toward and from the axis of the guide ring, and means for holding the pivot means against rotation.

11. A turret mechanism comprising a base having a peripheral flange and an upstanding central structure projecting above the flange, said central structure including a circular guide ring, a revolute turret resting upon the flange, and a plurality of guiding members mounted on the turret and disposed about said central upstanding structure; each said member comprising a roller engageable with the guide ring for guiding the turret in its revolution, a pivot pin rotatable in a bearing on the turret and providing a bearing for the roller, one of said bearings being eccentric to the other whereby a rotation of the pivot pin will produce movement of the roller toward and from the axis of the guide ring, and means connected to the turret for holding said pivot pin against rotation.

12. A turret mechanism comprising a base having a peripheral flange and a central upstanding structure projecting beyond the flange, a circular ring secured to said upstanding structure above the flange, a revolute annular turret resting upon the flange, and a plurality of guiding members mounted on the turret and disposed about the inner periphery of the same; each said member comprising a roller engageable with the hardened ring for guiding the turret in its rotation, a pivot pin having a bearing in said turret to determine its axis of rotation and also providing a bearing for the roller, said roller bearing being eccentric to the pivot axis whereby rotation of the pivot pin will produce movement

of the roller toward and from the central axis, said pivot pin also having a conical portion concentric with its axis, a clamping member having a conical socket for receiving said conical portion and secured to the turret, and a clamping plate engageable with said pin for pressing the conical portion into said socket whereby to prevent rotation of the pin about its axis, and means for pressing said plate against the pin.

13. A turret mechanism comprising a hollow base and an annular turret structure rotatable about a vertical axis relative to said base, indexing means for intermittently moving the turret structure including a source of power and devices driven thereby for moving said structure, a platform in the hollow base and having parts of the said devices secured thereto, and threaded means engaged with the platform for raising and lowering the same and including a spindle extending upwardly through the turret structure and accessible above the same.

14. A turret mechanism as in claim 13, in which the threaded means may be separated from the platform upon actuation of the spindle, and including locating means in the base for determining a position of the platform in which the threaded means may be engaged therewith and from which it may be raised for presenting the said parts in position for moving the turret structure.

15. In a turret mechanism, a base, a turret rotatable relative to said base, a bearing between said turret and base, power driven means for rotating the turret in either direction and including a skew-driving pinion and a meshing skew gear on the turret, and selecting means for controlling the turret rotating means whereby to effect a long forward movement of extent greater than a predetermined indexing movement and thereafter by reversal of the rotation of said skew pinion to effect a short retrograde movement, said skew pinion and skew gear being effective by their reaction during the forward movement to effect a reduction of the pressure friction between the turret and the base and during the retrograde movement to increase said pressure friction.

16. In a turret mechanism, a base, a turret rotatable about a vertical axis, bearing means on the turret and base for supporting at least a part of the weight of the turret, power driven means for rotating the turret in either direction and including a skew driving pinion and a meshing skew gear on the turret, and selecting means for controlling the turret rotating means whereby to effect forward and retrograde movements thereof by reversing the direction of movement of the driving pinion, said skew pinion and skew gear being effective by their reaction during the forward movement to reduce the pressure of the turret at said bearing means and during retrograde movement to increase said pressure.

17. In a driving system for a turret or like structure which is to be moved successively through predetermined intervals, a reversible source of power, means driven from the source of power to actuate the structure, stop means

for limiting retrograde movement of the structure upon reversal of the source of power and including cooperating interengageable parts for limiting the retrograde movement, one of said parts being movable relative to the other for permitting movement in the forward direction, a slip clutch included in said driving means for releasing the source of power from driving relationship with the structure when the parts of

5 said stop means are in effective engagement, means for initiating forward movement of the source of power, and means for controlling the forward and the reverse movement of said source of power including a control device actuated by 10 said relative movement of said one part of the stop means for assuring the continued forward movement through a predetermined distance.

18. In a driving system for a turret or like structure which is to be moved successively through predetermined intervals, a reversible source of power, means driven from the source of power to actuate the structure, stop means for limiting retrograde movement of the structure upon reversal of the source of power and including cooperating interchangeable parts for limiting the retrograde movement, one of said parts being movable relative to the other for permitting movement in the forward direction, a slip clutch included in said driving means for 20 releasing the source of power from driving relationship with the structure when the parts of said stop means are in effective engagement, means for initiating forward movement of the source of power, and means for controlling the 25 continued forward and reverse movement of said source of power including a control device actuated by said relative movement of said one part of the stop means for controlling the direction of energization of said source of power.

19. A driving system for turret and like machines which include relatively fixed and movable structures, comprising a reversible source of power, means driven from the source of power to actuate the movable structure, stop means for 30 limiting retrograde movement of the movable structure, including cooperating parts upon each of said structures, one of said parts having a stop element which is movable relative to the other said part in a direction at an angle to the direction of movement of the movable structure, at 35 least one of said parts including surfaces for producing a said relative movement of said element and for holding said element in its moved position during a predetermined travel of the movable structure, means included in said parts for returning said element from its moved position upon the completion of said predetermined travel, means for initiating forward movement of source of power, and means responsive to the 40 position of said element for effecting the continued forward movement of said movable structure for said predetermined travel and for provoking a reverse movement thereof when said element is returned.
